(57) **CLAIM**

The ornamental design for laptop with a retractable screen, as shown and described.

DESCRIPTION

1. Laptop with a retractable screen

1.1 : Perspective view in unfolded position

1.2 : Front

1.3 : Back

1.4 : Right

1.5 : Left

1.6 : Perspective view in folded position

1.7 : Right

1.8 : Left

1.9 : Perspective view in closed position

1.10 : Right

1.11 : Left

1.12 : Top

1.13 : Bottom

1.14 : Back

Reproductions 1.1 to 1.5 show the claimed design that a screen has been unfolded; reproductions 1.6 to 1.8 show the claimed design that a screen has been folded; reproductions 1.9 to 1.14 show the claimed design that a screen has been closed.

The broken lines and solid black coloring depict portions of the laptop with a retractable screen that form no part of the claimed design.

The stipple shading represents a contrasting appearance.

1 Claim, 14 Drawing Sheets
